UNITED STATES PATENT OFFICE.

EMIL PRICE AND WILLIAM A. PFISTER, OF LOS ANGELES, CALIFORNIA.

DESIGN FOR A VALVE FITTING.

Application filed May 15, 1928. Serial No. 26,680. Term of patent 14 years

To all whom it may concern:

Be it known that we, EMIL PRICE and WILLIAM A. PFISTER, citizens of the United States of America, and residents of Los Angeles, in the county of Los Angeles and State of California, have invented a new, original, and ornamental Design for a Valve Fitting, of which the following is a specification, reference being had to the accompanying drawings, forming part thereof.

In the drawings,

Figure 1 is a view in plan of the valve fitting;

Figure 2 is a perspective view thereof;

Figure 3 is an end view thereof; and

Figure 4 is a transverse section through the fitting on line 4—4 of Figure 2.

We claim:

The ornamental design for a valve fitting, as shown.

EMIL PRICE.

WILLIAM A. PFISTER.
